UNITED STATES PATENT OFFICE.

JOHN B. STUMPF, OF KALAMAZOO, MICHIGAN.

ROTARY ENGINE.

No. 807,975.

Specification of Letters Patent.

Patented Dec. 19, 1905.

Application filed May 17, 1905. Serial No. 260,825.

To all whom it may concern:

Be it known that I, JOHN B. STUMPF, a citizen of the United States, residing at Kalamazoo, in the county of Kalamazoo and State of Michigan, have invented new and useful Improvements in Rotary Engines, of which the following is a specification.

This invention relates to a rotary impact-engine which may be driven by steam, compressed air, or other fluids of any kind, the device consisting of a very simple, compact, and durable mechanism which forms an engine of very low cost, and owing to its simplicity it is easily operated and requires but little repair.

In the accompanying drawings, Figure 1 is an end elevation of the engine with one end of the cylinder removed. Fig. 2 is a side view of the piston removed from the cylinder. Fig. 3 is a perspective of the end or cover of the cylinder removed.

Referring specifically to the drawings, 6 indicates a cylindrical casing, 7 being the removable ends on same. The piston rotates in this casing. The piston consists of blades 8, mounted on or extending from the hub 9 on the shaft 10. These blades are arranged alternately on the hub or are staggered and are of less width than the cylinder, so as to provide passages around the inner edge of the blade from one blade to the next, thus making a series of alternate passages around the hub in the cylinder. The blades extend approximately each two-thirds across the space between the heads or ends of cylinder, thus leaving a passage of one-third the space between the heads. The hub 9 is preferably octagonal in cross-section, around which are arranged eight blades; but any other number or shape may be employed. The blades 8 are attached to the hub by being inserted in grooves in the hub, as shown in Fig. 2 at 11; but they may be bolted onto flanges or secured in other ways. While the blades could be cast on, I prefer to employ thin blades of steel attached in the manner shown. The blades are set at an acute angle to the axis of the shaft, with the alternate blades oppositely, so that they incline toward each other, and the motive fluid is thereby caused to rebound or flow from one blade to the next, striking the same at a fair angle to exert a powerful impact, and so on around the piston.

The shaft 10 has suitable bearings on the heads of the cylinder. An inlet-pipe for admitting steam to cylinder is indicated at 12 and of course has suitable valve for controlling the same. The inlet-pipe enters the cylinder near the top thereof and delivers the motive fluid tangentially to the blades. 13 60 is the exhaust-pipe, leading from the side of cylinder just below the inlet, so that the fluid traverses nearly the entire circumference of the cylinder.

It will be seen from the foregoing description that I provide a very simple and effective engine having a small number of parts, and consequently being easily understood and operated by any one. The engine is adapted to run at a very high rate of speed when desired 70 and is a very effective motor for running boats, vessels, vehicles, &c., and may also be used for any industrial purpose.

What I claim as new, and desire to secure by Letters Patent, is—

1. In a rotary engine, in combination, a cylinder having circumferential inlet and outlet, a shaft extending across the cylinder, and a piston on the shaft comprising a plurality of blades mounted on the shaft at an acute angle to the axis thereof and staggered with respect to each other and in contact alternately with the heads of the cylinder.

2. In a rotary engine, the combination with the cylinder having a tangential inlet, and an exhaust, of a shaft therein, and a piston comprising a plurality of blades mounted on the shaft at alternately-opposite angles to each other, said blades being of less width than the space between the heads of the cylinder and staggered to alternately contact with said heads.

3. In a rotary engine, in combination, a shaft, a hub thereon having grooves at alternately-opposite angles to the axis of the shaft, and blades fixed in said grooves.

In testimony whereof I have signed my name to this specification in the presence of two subscribing witnesses.

JOHN B. STUMPF.
